AUTOMATIC SAFETY READJUSTMENT
MECHANISM FOR NEWSPAPER PRESS
FOLD ROLLERS

Leslie J. Griner, Detroit, Mich.

Application February 4, 1952, Serial No. 269,764

12 Claims. (Cl. 270—76)

1

This invention relates to newspaper printing presses and the like, and in particular to safety devices for such presses.

One object of this invention is to provide an automatic safety readjustment mechanism for the folding rolls of newspaper printing presses which will operate automatically to move the folding rolls of the newspaper press rapidly toward one another in the event that one of the webs of paper accidentally breaks, so as to prevent jamming known as folder chokes, which occurs when such web breakage takes place.

Another object is to provide an automatic safety readjustment mechanism of the foregoing character, wherein the breaking of one of the paper webs actuates devices operated by electricity, pressure fluid or mechanical means, so that the folding rolls which grip and deliver the folded newspaper after its printed sheets have been printed, cut and folded are almost instantaneously pushed toward one another to diminish the gap between them so that they will still grip and feed the remainder of the folded newspaper and eject it from the machine, even though the breakage of one of the webs fails to supply the folding rolls with a portion of the paper.

Another object is to provide an automatic safety readjustment mechanism of the foregoing character, which will prevent the serious damage previously occurring in such presses as a result of the paper from the unbroken web piling up in the folding mechanism and jamming there, by reason of the inability of the folding rolls to grip a thinner body of folded paper than it has been adjusted to handle.

Other objects and advantages of the invention will become apparent during the course of the following description of the accompanying drawing, wherein:

Figure 1 is a diagrammatic side elevation, partly in vertical section, of the newspaper cutting and folding machinery of a conventional newspaper printing press, equipped with an automatic safety readjustment mechanism according to one form of the invention in which the mechanism is operated electro-magnetically;

Figure 2 is an approximately horizontal section taken along the line 2—2 in Figure 1;

Figure 3 is an approximately horizontal section taken along the line 3—3 in Figure 1, showing a part of the folding roll readjusting mechanism;

Figure 4 is a diagrammatic side elevation partly in vertical section, of a machine similar to that shown in the left-hand half of Figure 1, but

2

equipped with a modified safety readjustment mechanism for the folding rolls in which the readjustment mechanism is operated electro-pneumatically;

Figure 5 is a diagrammatic side elevation of a machine similar to that shown in the left-hand half of Figure 1, but equipped with a further modified safety readjustment mechanism for the folding rolls in which the readjustment mechanism is operated wholly mechanically; and

Figure 6 is a fragmentary side elevation, partly in vertical section, of the central portion of the machine of Figure 1, equipped with a still further modified web breakage detector operated by a photo-electric cell for actuating the safety readjustment mechanism photo-electrically.

Summary of the invention

Modern newspaper printing presses operate at high speed to unwind multiple strips of paper from multiple rolls of newsprint paper, print the text and illustrations thereon, deliver the combined strips to folding machinery which combines them into multi-sheet webs and forms the first and second folds therein and cuts off the thus combined and folded sheets and delivers them to a conveyor for transportation to the trucks which carry them to the news vendors. Modern newspapers sometimes run as high as 96 sheets per issue, made up in two or more sections which are individually folded together by the coming together of two or more multi-sheet webs from different portions of the printing press. After the webs have been folded vertically and cut, they are then given their second or horizontal fold into finished newspapers by being grasped between the so-called second fold rollers, working in conjunction with a so-called tucking blade which tucks the paper down between the fold rollers, which are adjusted at a sufficient spacing from one another and corrugated to properly grip the folded newspaper.

These presses operate at tremendous speeds, some of them delivering as many as 36,000 news-papers per hour as thick as 96 pages each, with the paper webs moving at speeds approximating 1200 feet per minute. Since newsprint paper has a comparatively low tensile strength, occasionally one of the two printed webs will accidentally break, terminating the flow of paper from one half of the machine. When this occurs, the paper which the tucking blade tucks down between the second fold rollers is only half the thickness for which the spacing of the rollers has been adjusted, with the result that the second

fold rollers do not exert a sufficient grip to eject the folded newspaper. Meanwhile, however, other half newspapers are being fed rapidly into the second fold rollers with the result that a serious jamming of the machinery occurs by the inability of the second fold rollers to carry away the newspaper. If the newspaper press is not halted immediately, the newspapers pile up in the fold rollers and are jammed tightly between them by the tucking blade. This jamming of the press sometimes smashes the machinery and causes many thousands of dollars damage almost in the twinkling of an eye.

Previous attempts have been made to minimize the damage caused by such "folder chokes," as they are known in the newspaper business, such as by providing mechanism to release springs which normally urge the fold rollers together so as to separate the second fold rollers. Other devices have been developed to close a stop circuit for halting the press motors when one of the paper webs breaks. Such devices, however, operate too slowly to be effective with modern high speed presses, as the damage occurs before effective measures can be taken to stop the press or remove the papers from the second fold rollers, due to the high speed and momentum of modern presses.

The safety device of the present invention, in contrast to prior safety devices, instead of attempting to provide greater space for the newspapers by trying to separate the second fold rollers, adopts the opposite remedy of suddenly forcing the second fold rollers closer together immediately upon the breaking of one of the webs of paper. This readjustment mechanism is set in motion by a detector located prior to the entrance point of the paper webs into the second fold mechanism, and operates to actuate an electric circuit or set in motion a train of mechanism which almost instantaneously pushes one of the second fold rollers toward the other, halving the distance between them so that the second fold rollers are now able to effectively grip the half-sized paper resulting from the supplying of only one web to the second fold mechanism. Various arrangements are shown in the drawings for accomplishing the shifting of the second fold rollers, that in Figure 1 being effected electro-magnetically, in Figure 4 electro-pneumatically, in Figure 5 merely mechanically, and in Figure 6 photo-electrically.

Electro-magnetic safety fold roller readjustment mechanism

Referring to the drawings in detail, Figures 1 to 3 inc. show a safety readjustment mechanism, generally designated 10, as applied to the folding and cutting mechanism, generally designated 11, of a conventional high speed newspaper printing press, generally designated 12. The folding and cutting mechanism 11 in turn consists of two assemblies, generally designated 13 and 14 respectively occupying the right-hand and left-hand sides of Figure 1. The folding and cutting assemblies 13 and 14 are substantially duplicates, hence a description of one will suffice for both. The printed newspaper sheets from the two sections of the newspaper being printed and folded together form multiple-sheet or multiple-strip webs 15 and 16 respectively, both being combined in one of the assemblies 13 and 14 to form the newspaper. The assemblies 13 and 14 are otherwise not in simultaneous use, except in making the first fold of the newspaper by the aid of the first

folding units, generally designated 17. Only one unit of the pair of second folding and cutting units, generally designated 18, is in use at any one time, the other being maintained in a stand-by condition for use in an emergency in the event of breakdown or for repairs.

The paper webs 15 and 16 coming from the printing section of the printing press 12 pass over rollers 19 mounted on shafts 20 journaled in the frame side structures 21 and 22 respectively, the frame side structures being in turn interconnected by cross members 23 to 26 inc. to form the frame, generally designated 27. The webs 15 and 16 each have as many sheets or layers as the number of pages allotted to that particular portion of the newspaper, the number varying according to the day of the week and the amount of material to be published. As the multi-sheet web approaches the first folding unit 17, its 15 right-hand and left-hand halves are folded vertically on their center line through an angle of 90° to their former plane, namely from the plane of the paper to a plane perpendicular to the paper in Figure 1. This so-called first fold is facilitated by means of upper and lower approximately triangular guide structures 28 and 29 and by means of upper and lower pairs of first fold rollers 30 and 31 respectively mounted on shafts 32 and 33, respectively. The shafts 32 and 33 are journaled at their opposite ends in supports 34, only one of which is shown, and which rise from the cross members 25 of the frame 27. The multi-sheet web 16 from the assembly 14 after being folded vertically in halves, as described above, passes directly downward to the second fold and cutting unit 18 which is then in use, the other unit 18 being idle. The folded web 15 in the assembly 13, however, passes in an approximately horizontal direction from its respective first fold unit 17 over a guide roller 35 journaled in bearing blocks 36 secured to one of the side structures 22 when it passes downward under a swinging guide roller 37 journaled as at 37 in the lower ends of arms 38, the upper ends of 35 which are pivotally mounted and journaled as at 40 in the side frame structure 22. Beyond the swinging guide roller 37, the web 15 passes substantially horizontally to a guide roller 41 mounted on a shaft 42 which is journaled at its opposite ends in the supports 34, after which it proceeds downward into the second folding and cutting unit 18 which is in use at that particular time.

The two longitudinally folded multi-sheet webs 15 and 16 pass downward into the space between a cutting cylinder unit 45 and a cooperating folding cylinder unit 46. The cutting cylinder unit 45 consists of a cylinder 47 mounted upon a horizontal shaft 48, the opposite ends of which are 60 journaled in bearing blocks 49 which are slidably mounted in horizontal guideways 50 (Figure 1) and urged toward the folding unit 46 by compression springs 51, the guideways 50 being mounted on or in the frame cross members 25. 65 Mounted on the cutting cylinder 47 is a transversely disposed sharp-edged cutting blade 52 which is adapted to sever the longitudinally-folded webs 15 and 16 just below the point where they are engaged by the cutting cylinder unit 45 and folding cylinder unit 46. In this manner, the webs 15 and 16 remain in engagement with the units 45 and 46 even though severing has taken place immediately below their point of engagement (Figure 1). The cutting blade 52 is ordinarily equipped with a sliding guard (not shown)

which forms no part of the present invention and which is therefore omitted in order to show the construction more clearly.

The cutting and folding cylinder units 45 and 46 are positively geared to one another in order that they shall rotate in a definite timed relationship. For this purpose, a gear 53 is keyed or otherwise drivingly secured to the end of the shaft 48 and in turn meshes with a gear 54 keyed or otherwise drivingly secured to a shaft 55 by which the folding cylinder unit 46 is driven. Mounted on the shaft 55 (Figure 1) is a cylinder 56 which is substantially twice the diameter of the cutting cylinder 47 and which at diametrically opposite locations is provided with transversely-disposed pads or cushions 57 and 58 of resilient material such as rubber, synthetic rubber or the like. The gearing 53, 54 is so proportioned and arranged that the pads 57 and 58 arrive opposite the edge of the cutting blade 52 after each revolution of the cutting cylinder 47. Accordingly, the pitch diameter of the gear 54 is twice the pitch diameter of the gear 53, and has twice the number of teeth. If, however, the cylinders 47 and 56 were made of different ratios of diameters, the ratios of the gears 53, 54 would be correspondingly changed.

The shaft 55 upon which the folding cylinder 56 is mounted is journaled at its opposite ends in the cross members 25. Keyed or otherwise secured to the shaft 55 (Figure 2) is a driving gear 57 which is in turn driven by another motor-driven gear (not shown), or which is driven from other rotating parts of the printing press 12. The folding cylinder 56 at its opposite ends is provided with end plates 56a in the form of discs which close the opposite ends of the cylinder 56 and which at diametrically opposite locations are provided with cutaway portions 60 in which are mounted bearing blocks or journal bearings 61 rotatably supporting tucking shafts 62. Mounted on each tucking shaft 62 and rotated thereby is a tucking blade 63. Keyed or otherwise secured to one end of each tucking blade shaft 62 is a pinion 64 (Figure 2), which meshes with and rolls around upon a stationary internal gear 65 having gears 66 by which it is bolted or otherwise secured to the frame cross members 25 and 34 respectively. In this manner, the tucking blades 63 rotate relatively to the cylinder 56 and, having lengths sufficient to cause them to project outwardly beyond the cylinder 56 when they swing through the transverse peripheral apertures 67 thereof (Figure 2), shown in the lower portion of Figure 1. The tucking blades 63 and their pinions 64 are so mounted that the blades project through the apertures 67 when they reach their lowermost positions (Figure 1). The apertures 67 are spanned by arcuate bridge member 68 (Figure 2) which are mounted at transversely-spaced locations across the periphery of the cylinder 56 and go flush with the peripheral surface 69 thereof. These bridge members 68 engage the multi-sheet paper web 16 and prevent substantial bulging thereof into the apertures 67.

Journaled at diametrically opposite locations in the cylinder heads 58 are gripping pin shafts 70 disposed midway between the tucking blade shafts 62 around the periphery of the cylinder 56. Mounted on one end of each gripping pin shaft 70 is a crank arm 71 carrying a cam follower roller 72 (Figure 2) which engages the cam groove 73 in a stationary face cam or crown cam 74 which is provided with a bore 75 through which the cylinder shaft 55 loosely and rotatably passes.

The cam 74 is provided with a hub 76 which in turn is provided with ears 77 bolted or otherwise secured to one of the frame cross members 25 (Figure 2). Mounted upon each of the gripping pin shafts 70 are transversely spaced crank arms 78 to the ends of which are secured pointed paper gripping pins 79 which, like the tucking blades 63, are of excessive lengths so as to project through apertures 80 (Figure 1) adjacent the cushions 57 and 58. The paper gripping pins 79 are caused by the action of the cam rollers 72 on the crank arms 71 to be periodically advanced through the apertures 80 when the latter approach the cutting cylinder 47 so as to penetrate the paper webs 15 and 16 and pull them downward beneath the cylinder 56 to the location where one of the tucking blades 63 performs the tucking operation (Figure 1). In order to guide the severed lengths 81 and 82 which are cut off from the paper webs 15 and 16 by the cutting blade 52, and which form the newspaper 83, arcuate guide members 84 and 85 are provided and mounted by brackets 86 and 87 (Figure 1) on the frame cross members 26.

Mounted immediately below the folding cylinder unit 46 is the second fold roller assembly, generally designated 90 (Figure 3) which includes a part of the safety readjustment mechanism 10 and also forms a part of the second folding and cutting unit 19. The second fold roller assembly 90 includes stationary and shiftable second fold rollers 91 and 92 respectively (Figures 1 and 3). The stationary second fold roller 91 is stationary only in the sense that its axis remains stationary, because it is mounted upon and drivingly secured at its opposite ends to stub shafts 93 and 93a which are journaled in bearing blocks 94 bolted to the frame cross members 26. The shaft 93 carries a gear 95 which is keyed or otherwise drivingly secured thereto and which meshes with a gear 96 keyed or otherwise drivingly secured to the shaft 55 (Figure 2). The roller 91 also carries a gear 97 (Figure 3) which is likewise drivingly secured thereto and which meshes with a gear 98 drivingly secured to the shiftable fold roller 92. The teeth of the gears 97 and 98 are sufficiently long to enable the shiftable roll 92 to be moved nearer to or farther away from the stationary roll 91 in order to vary the gap 99 between them.

The shiftable roll 92 at its opposite ends is pinned or otherwise drivingly secured to stub shafts 100 (Figure 3) which are journaled in bearing blocks 101. The bearing blocks 101 are in turn mounted on the ends of non-rotatable screw shafts 102. Threaded upon each screw shaft 102 is an internally-threaded nut 103 (Figure 1) which is loosely and rotatably mounted in a bore 104 in a lever 105, one of which levers 105 is a bent lever provided with an arm 106. The levers 105 are in turn pivotally mounted upon pivot shafts 107. Each pivot shaft 107 is mounted upon a bracket 108 depending from one of the frame cross members 26. The threaded nuts 103 carry spiral or helical gears 109 which mesh with similar gears 110 with axes at right angles thereto. The gears 110 (Figure 3) are mounted upon and drivingly secured to a cross shaft 111 which is journaled near its opposite ends in bracket arms 112 extending outwardly from the bent levers 106. Mounted on one end of the shaft 111 is a handwheel 113 which in cooperation with the shaft 111, gears 110 and 109 and internally-threaded nuts 104 constitutes a manual roller adjustment mechanism, generally designated 114,

by which the bearing blocks 102 can be moved to and fro to consequently widen or narrow the gap 99 between the second fold rollers 91 and 92 (Figure 3). This adjustment is made whenever a number of sheets in the edition of the newspaper is changed and may vary between wide limits as, for example, between a Friday newspaper containing a large number of advertisements and a Saturday newspaper containing a very small number thereof. In order to increase the gripping effect of the second fold rollers 91 and 92, these are preferably provided with corrugated or knurled portions 115 (Figure 3). Stop pins 116 (Figure 1) mounted on the brackets 108 limit the rearward motion of the bent levers 106, and consequently limit the maximum width of the gap 99 between the second fold rollers 91 and 92.

Safety fold roller readjustment mechanism

Superimposed upon the manual roll adjustment mechanism, 114 is the safety roll readjustment mechanism 10 by which the second fold roller 92 may be suddenly and automatically moved toward the second fold roller 91 in order to narrow the gap 99 quickly in the event that one of the multi-sheet webs 15 or 16 breaks. In that event, the folding and cutting unit 18 which is in use at the moment and which is adjusted to engage the thickness of both webs 15 and 16 is now suddenly deprived of one web and hence the corrugated or knurled portions 115 lose their gripping power by the gap 99 being too wide for effectively gripping one web. The automatic safety readjustment mechanism 10 about to be described then comes into play automatically to narrow the gap 99 to approximately half of its previous width in order to effectively grip the single web remaining and thereby prevent the occurrence of a "folder choke" or piling up of the severed paper portions 81, 82 immediately adjacent the gap 99, with the consequent occurrence of serious damage to the printing press.

For this purpose, the arm 106 of the bent lever 105 is pivotally connected by links 117 to the armature 118 of a solenoid 119 which in turn is mounted upon a bed 120 supported by one of a pair of frame cross members 121 (one only being shown). Also mounted on the bed 120 and rising therefrom is an upright 122 having a horizontally adjustable stop screw 123 threaded through the upright 122 and with its end engageable with an auxiliary arm 124 of the bent lever 106. In the normal operation of the apparatus, as shown in Figure 1, a gap 125 ordinarily exists between the lever arm 124 and the end of the stop screw 123 which is, of course, locked in position by a lock nut 126. Connected to the upper end of the upright 122 is the lower end of a tension spring 127, the upper end of which is connected to the upper end of the bent lever 106 to urge it and the mechanism carried by it to the left against the stop pins 116.

Also mounted upon the bed 120 is a conventional relay switch 128 which serves to connect the solenoid energization lines 129 and 130 to the power lines 131 and 131a when the relay 128 is energized. The relay switch 128 is provided in order to permit the use of low voltage electric current in the control circuit of the safety roll readjustment mechanism 10, such as 25 volt current from a suitable transformer (not shown) for safety reasons to control the supply of the high voltage power current to the solenoid 119. The relay switch 128 is operated by control current 75 of the safety switch 134 remains held in a raised

reaching it through the relay control lines 132 and 133 (Figure 1) which are connected to a normally closed safety switch 134 mounted on an angle bracket 135 bolted or otherwise secured to one of the frame uprights 21. The safety switch 134 is provided with a swinging operating arm 136 mounted on a switch operating shaft 137 and carrying a contact roller 138 which rests upon and engages the web 15. The switch-operating arm 136 is normally urged downward by a spring or weight (not shown) within the switch 134, but is prevented from so swinging downward by the presence of the taut web 15, thus holding the switch operating arm 136 in a raised position, causing the switch 134 to be in its open circuit position, interrupting the flow of current from control current supply lines 139 and 140 to the relay control lines 132 and 233. From the lines 132 and 133, lines 132a and 133a run to the operating coil of a normally closed motor control relay switch (not shown) which opens the energization circuit of the press driving motor or motors when the lines 132a and 133a are energized.

Operation

In the operation of the invention, let it be assumed that the printing press, including the folding and cutting assemblies 13 and 14, is set up and in operation, as shown in Figure 1, with the already printed multiple sheet or multiple strip webs 15 and 16 running at high speed downward into the first folding units 17, and with the web 15 serving as a transfer web by being diverted from its own second folding and cutting unit 18 to the one located in the assembly 14, by means of the guide rollers 35, 37 and 41.

After the multiple sheet webs 15 and 16 have been folded longitudinally in the units 17 and have come together in the space between the cutting cylinder unit 45 and the folding cylinder unit 46, they are pulled downward simultaneously by the penetration of the paper gripping pins 79 which, at this instant, are caused by the action of the cam rollers 72 in the cam groove 73 of the cam 74 (Figure 2) to project through the aperture 80 beyond the peripheral surface 69 of the cylinder 56. Immediately below their meeting point, the webs 15 and 16 are engaged by the cutting blade 52 and are severed transversely by 50 being engaged by the cutting blade 52 on one side operating against the cushion 57 on the other side. The severed lengths 81 and 82 forming the two sections of the newspaper are now engaged by the lower tucking blades 63 which have been rotated in timed relationship downward into their projecting positions through the aperture 67 into engagement with the newspaper sections 81 and 82.

The tucking blades 63 make an indentation 139 60 midway between the upper and lower edges of the newspaper sections 81 and 82, as shown in Figure 1, folding the newspaper transversely and forcing the fold thereof down between the second fold rollers 91 and 92. This action brings the four 65 thicknesses of newspaper in the second fold 139 into gripping engagement with the corrugated or knurled portions 115 of the fold rollers 91 and 92, which carry the folded newspaper 83 downward and discharge it onto a conveyor (not shown) 70 which carries it to a point of packing for distribution.

During normal running operations, the webs 15 and 16 remain in a taut condition and consequently the roller 138 on the operating arm 136 75 of the safety switch 134 remains held in a raised

position, holding the normally closed switch 134 in open circuit. If, however, the web 15 breaks, the arm 136 immediately drops, closing the control circuit through the switch 134 and energizing the relay 128 from the now energized relay control lines 132 and 133 which are now receiving current from the control current from the control current supply lines 140 and 140a. At the same time, the lines 132a and 133a are likewise energized, operating a relay (not shown) which 10 energizes, operating a relay (not shown) which 10 halts the press driving motor or motors.

The energization of the relay switch 128 by this means closes the circuit between the power lines 131 and 131a. The consequent energization of the solenoid 119 instantly pulls its armature 118 downward, likewise pulling the arm 108 of one of the levers 105 downward, shifting the levers 105 in a clockwise direction and consequently shifting the second fold roller 92 toward the stationary second fold roller 91 until the third arms 124 of 20 the levers 105 engage the stop screws 123. Meanwhile, the gap 99 has been narrowed by this action so that the corrugated or knurled portions 115 of the rollers 91 and 92 engage the transversely-folded section 81 of the single web 16, feeding it downward between the rolls and ejecting it from the printing press. In this manner, the sections 82 are prevented from piling up beneath the cylinder 56 as they would do if the automatic safety readjustment mechanism 10 of the present invention were not provided.

Fluid-operated safety fold roller readjustment mechanism

The fluid-operated safety fold roller readjustment mechanism, generally designated 150 shown in Figure 4, is generally similar to the mechanism 10 shown in Figures 1 to 3 inclusive and differs only in the means for shifting the levers 105, the additional corresponding to the arm 108 being here designated 151. Similar parts of Figure 4 are designated with the same reference numerals as the corresponding parts in Figure 1. In Figure 4, one of the levers 105 has a downwardly projecting arm 152 with stop portions 153 engaging the stop screws 123 when the web breaks and the safety mechanism becomes operative. The lever arm 151 is normally urged forwardly by a tension spring 154 secured thereto at its rearward end and secured at its forward end to a post 50 or ear 155 projecting upward from the rearward cylinder head 156 of the cylinder 157 of a fluid pressure motor, generally designated 158. The motor 158 has a forward cylinder head 159, both cylinder heads 156 and 159 being bolted or otherwise secured to the bed 120 previously mentioned. Reciprocably mounted in the cylinder 157 is a piston 160, the piston rod 161 of which is pivotally connected by a link 162 to the lower end of the lever arm 151.

The fluid pressure motor 158, preferably a pneumatic motor, is supplied with pressure fluid through a pipe 163 from a conventional rotary valve 164 which in turn is connected to a pressure fluid supply line 165 and a discharge pipe 166. The valve 164 is provided with an operating shaft 167 which in turn carries an operating arm 168 suitably connected as by a pin and slot connection at the point 169 to the armature 118 of the solenoid 119, as before. The latter is connected to the relay switch 128 and the relay switch 128 to the safety switch 134 in the manner described in connection with Figure 1.

The operation of the modification shown in Figure 4 is in most respects similar to that of the 75

form of the invention shown in Figure 1. When the web 15 breaks, it permits the switch arm 136 to swing downward, energizing the relay switch 128 and solenoid 119 as before. The consequent shifting of the solenoid armature 118, however, now swings the valve operating arm 168, causing pressure fluid such as compressed air to pass from the supply line 165 to the service line 163 of the fluid pressure motor 158. This causes the piston 160, piston rod 161 and lever arm 151 to move to the left, swinging the levers 105 clockwise to the right around their pivot shafts 107 (Figure 4), thus narrowing the gap 99 between the fold rollers 91 and 92 and permitting them to grip the severed and folded newspaper sections 82 in the absence of the sections 81, resulting from the breakage of the web 15. Thus, the fold roller readjustment mechanism 150 of Figure 4 likewise prevents the piling up of the completely folded newspaper sections 82 and ejects them downward between the rollers 91 and 92 as before.

Mechanical safety fold roller readjustment mechanism

The mechanical safety fold roller readjustment mechanism, generally designated 170 shown in Figure 5, is similar in many respects to the mechanism shown in Figures 1 and 4, and differs only in the means for shifting the levers 105. The shifting mechanism of Figure 5 is purely mechanical and for this purpose one of the levers 105 is provided with a pair of arms 171 and 172 arranged in approximately horizontal and vertical directions respectively. Connected to the horizontal arm 171 is a tension spring 173 which is anchored to an angle bracket 174 bolted to the bed 120. The spring 173 urges the levers 105 and their accompanying parts, including the shiftable second fold roller 92 to the right. The second arm or vertical arm 172 is adapted to engage the stop screw 123 in the upright 122 when permitted to do so by a bent latch lever 175. The latter is pivotally mounted upon a pivot shaft 176 mounted upon a bracket 177 bolted to the bed 120, and at one end carries a catch or projection 178 and at its other end is provided with a pivotal connection 179 to a link 180. The link 180 is pivotally connected as at 181 to a bent lever 182 pivotally mounted upon a pivot shaft 183 mounted upon a bracket 184 likewise bolted to the bed 120. The other end of the bent lever 182 is pivotally connected as at 185 to the lower end of a vertical link 186, the upper end of which is pivotally connected as at 187 to a downwardly swinging contact arm 188 having a contact roller 189 pivotally mounted at 190 thereon. The right-hand or inner end of the contact arm 188 is pivotally mounted at 191 on a bracket 192 which is bolted or otherwise secured to one of the frame uprights 21. The roller 189 is adapted to rest upon the taut web 15 as before.

In order to halt the printing press, however, when breakage of the web 15 occurs, the contact arm 188 is also pivotally connected at 187 to the lower end of a link 193, the upper end of which is pivotally connected as at 194 to the swinging operating arm 195 of a safety stop switch 196. The latter is normally open but closes when the operating arm 195 swings downward so as to close the circuit between the control lines 197 and 198. These form a part of the energization circuit of another relay (not shown) which in turn controls the halting of the driving motor or motors of the printing press.

Assuming the parts to be in the positions

11

shown in Figure 5, with the levers 170 locked in their outer positions by the latch projection 178 upon the lever 175 engaging the arm 172 on one of the levers 170, the multiple paper webs 15 and 16, as before, move continuously downward and are cut off into the lengths 81 and 82 and carried downward to the second fold rollers 91 and 92, and folded by the tucking blades 63 and ejected downward between the rollers 91 and 92. When the web 15 breaks, however, the contact arm 188 swings downward, moving the links 186 and 193 downward. The latter closes the safety switch 196 to energize the control lines 197 and 198 in order to stop the printing press motor or motors while the former swings the bent lever 182 in a clockwise direction. This shifts the link 188 to the left (Figure 5), swinging the latch lever 175 downward and withdrawing the latch projection 178 from engagement with the lower end of the downwardly-projecting lever arm 172. This releases the levers 105 from their locked positions, whereupon the spring 173 pulls the lever arm 171 downward, swinging the levers 170 to the right and with them the shiftable second fold roller 92. This narrows the gap 99 between the second fold rollers 91 and 92 as before, causing these rollers to firmly grip the folded single section 82 of the newspaper in the absence of the second section 81, which is missing as a result of the breaking of the web 15. The single newspaper sections 82 are thus folded and ejected downwardly between the second fold rollers 91 and 92, as if no breakage had occurred, thus preventing a "fold choke" and consequently preventing damage to the apparatus.

Meanwhile, the closing of the safety switch 196 by the breakage of the paper web 15 has halted the printing press motor or motors, bringing the printing press to a stop. Since these printing presses operate at high speeds, however, the momentum of the various rotating parts would continue the cylinders 47 and 56 in rotation a sufficient distance to cause a fold choke if the safety mechanism of the present invention were not provided.

Photo-electric actuating device for readjustment mechanism

Figure 6 shows a photo-electric device, generally designated 200, which takes the place of the safety switch 134 and eliminates the necessity for direct physical contact between a roller or contact member, such as the roller 138 and contact arm 136 with the web 15. Instead, the actuating device 200 is provided with a light source 201 mounted on an angle bracket 202 bolted to one of the frame uprights 21 and energized through the lines 203 and 204 from any suitable source of electricity. The light source 201 is placed immediately above the paper web 15 and in line with a photo-electric cell 205 placed below the web 15 and connected to the control lines 132 and 133 controlling the actuation of the relay switch 128 of Figure 1 or 4. From the control lines 132 and 133, auxiliary control lines 206 and 207 run to another relay (not shown) which controls the motor stopping switch in a manner similar to the control lines 197 and 198 described in connection with Figure 5.

In the operation of the actuating device 200 of Figure 6, the machinery is assumed to be running as described in connection with Figure 1, with the parts in positions shown in Figure 1

12

or Figure 4, depending upon whether the mechanism is to be shifted directly by the electric solenoid 119 (Figure 1) or indirectly by the pressure fluid motor 158 regulated by the valve 164 operated by the solenoid 119 (Figure 4). The light source 201 is energized so as to project light rays downward toward the photo-electric cell 205.

So long as the multiple sheet paper web 15 remains running and unbroken, it intercepts all the light from the light source 201 and prevents it from reaching the photo-electric cell 205. Immediately upon breakage of the web 15, however, light from the light source 201 reaches the photo-electric cell 205, energizing the control lines 132, 133, 206 and 207. The energization of the control lines 132 and 133 energizes the relay switch 128 (Figure 4) and consequently energizes the relay 119. The mechanism then operates in the manner described above to shift the movable second fold roller 92 toward the stationary second fold roller 91 to narrow the gap 99 between them and continue to grip the folded single newspaper sections 82 reaching them in the absence of the sections 81 resulting from the breakage of the web 15. The folded single sections 82 are thereby gripped between the second fold rollers 91 and 92 and ejected downwardly between them without damage to the machinery and without causing the fold choke.

The energization of the lines 206 and 207 (Figure 6) causes the energization of a second relay (not shown), which actuates a motor stop switch (not shown) so as to halt the press driving motor or motors. Here again, however, the momentum of the machinery caused by the high operating speeds involved would otherwise cause the cylinders 45 and 56 to continue rotation a sufficient amount to cause a fold choke if the automatic safety fold roller readjustment mechanism of the present invention were not provided.

What I claim is:

1. An automatic safety readjustment device for a newspaper printing press having paired second fold rollers and an adjacently-disposed folding-and-tucking cylinder and blade cooperating therewith uniting two separate multi-strip continuously running paper webs proceeding to a junction at said cylinder along two separate web paths, said device comprising a shiftable support mounted on said press and carrying one of said fold rollers, mechanism operatively connected to said support for shifting said support and the fold roller carried thereby toward the other fold roller of the pair to narrow the gap therebetween, and a web breakage detector disposed adjacent one of said webs on one of said separate paths and operatively connected to said mechanism, said web breakage detector being responsive to the breakage of said web for energizing said mechanism to shift said support and the fold roller carried thereby toward said other fold roller and reduce the space between said rollers in consequence of the reduction in number and thickness of the webs being fed through said rollers resulting from the breaking of said one web whereby to instantly regrip the reduced-thickness remaining web tightly between said rolls and prevent jamming thereof.
2. An automatic safety readjustment device for a newspaper printing press having paired second fold rollers and an adjacently-disposed fold-

ing-and-tucking cylinder and blade cooperating therewith uniting two separate multi-strip continuously running paper webs proceeding to a junction at said cylinder along two separate web paths, said device comprising a shiftable support mounted on said press and carrying one of said fold rollers, mechanism operatively connected to said support for shifting said support and the fold roller carried thereby toward the other fold roller of the pair to narrow the gap therebetween; and a web breakage detector disposed in engagement with one of said webs on one of said separate paths and operatively connected to said mechanism; said web breakage detector being movable in response to the breakage of said web for energizing said mechanism to shift said support and the fold roller carried thereby toward the other fold roller and reduce the space between said rollers in consequence of the reduction in number and thickness of the webs being fed through said rollers resulting from the breaking of said one web whereby to instantly regrip the reduced-thickness remaining web tightly between said rolls and prevent jamming thereof.

3. An automatic safety readjustment device for a newspaper printing press having paired second fold rollers and an adjacently-disposed folding-and-tucking cylinder and blade cooperating therewith uniting two separate multi-strip continuously running paper webs proceeding to a junction at said cylinder along two separate web paths, said device comprising a shiftable support mounted on said press and carrying one of said fold rollers, electrically-controlled mechanism operatively connected to said support for shifting said support and the fold roller carried thereby toward the other fold roller of the pair to narrow the gap therebetween; and a web breakage detector disposed adjacent one of said webs on one of said separate paths and operatively connected to said mechanism; said web breakage detector being responsive to the breakage of said web for energizing said mechanism to shift said support and the fold roller carried thereby toward the other fold roller and reduce the space between said rollers in consequence of the reduction in number and thickness of the webs being fed through said rollers resulting from the breaking of said one web whereby to instantly regrip the reduced-thickness remaining web tightly between said rolls and prevent jamming thereof.

4. An automatic safety readjustment device for a newspaper printing press having paired second fold rollers and an adjacently-disposed folding-and-tucking cylinder and blade cooperating therewith uniting two separate multi-strip continuously running paper webs proceeding to a junction at said cylinder along two separate web paths, said device comprising a shiftable support mounted on said press and carrying one of said fold rollers, electrically-controlled mechanism operatively connected to said support for shifting said support and the fold roller carried thereby toward the other fold roller of the pair to narrow the gap therebetween; and a web breakage detector disposed adjacent one of said webs on one of said separate paths and operatively connected to said mechanism; said web breakage detector including an electric switch responsive to the breakage of said web for energizing said mechanism to shift said support and the fold roller carried thereby toward the other fold roller and reduce the space between said rollers.

in consequence of the reduction in number and thickness of the webs being fed through said rollers resulting from the breaking of said one web whereby to instantly regrip the reduced-thickness remaining web tightly between said rolls and prevent jamming thereof.

5. An automatic safety readjustment device for a newspaper printing press having paired second fold rollers and an adjacently-disposed folding-and-tucking cylinder and blade cooperating therewith uniting two separate multi-strip continuously running paper webs proceeding to a junction at said cylinder along two separate web paths, said device comprising a shiftable support mounted on said press and carrying one of said fold rollers, electrically-controlled mechanism including an electromotive device operatively connected to said support for shifting said support and the fold roller carried thereby toward the other fold roller of the pair to narrow the gap therebetween; and a web breakage detector disposed adjacent one of said webs on one of said separate paths and operatively connected to said mechanism; said web breakage detector being responsive to the breakage of said web for energizing said mechanism to shift said support and the fold roller carried thereby toward the other fold roller and reduce the space between said rollers in consequence of the reduction in number and thickness of the webs being fed through said rollers resulting from the breaking of said one web whereby to instantly regrip the reduced-thickness remaining web tightly between said rolls and prevent jamming thereof.

6. An automatic safety readjustment device for a newspaper printing press having paired second fold rollers and an adjacently-disposed folding-and-tucking cylinder and blade cooperating therewith uniting two separate multi-strip continuously running paper webs proceeding to a junction at said cylinder along two separate web paths, said device comprising a shiftable support mounted on said press and carrying one of said fold rollers, electrically-controlled mechanism including an electromotive device operatively connected to said support for shifting said support and the fold roller carried thereby toward the other fold roller of the pair to narrow the gap therebetween; and a web breakage detector including an electric switch disposed adjacent one of said webs on one of said separate paths and operatively connected to said mechanism; said web breakage detector being responsive to the breakage of said web for energizing said mechanism to shift said support and the fold roller carried thereby toward the other fold roller and reduce the space between said rollers in consequence of the reduction in number and thickness of the webs being fed through said rollers resulting from the breaking of said one web whereby to instantly regrip the reduced-thickness remaining web tightly between said rolls and prevent jamming thereof.

7. An automatic safety readjustment device for a newspaper printing press having paired second fold rollers and an adjacently-disposed folding-and-tucking cylinder and blade cooperating therewith uniting two separate multi-strip continuously running paper webs proceeding to a junction at said cylinder along two separate web paths, said device comprising a shiftable support mounted on said press and carrying one of said fold rollers, electrically-controlled mechanism operatively connected to said support for shifting said support and the fold roller carried thereby

15

toward the other fold roller of the pair to narrow the gap therebetween, and a web breakage detector disposed adjacent one of said webs on one of said separate paths and operatively connected to said mechanism, said web breakage detector including a radiation source and a photoelectric cell associated therewith and responsive to the breakage of said web for energizing said mechanism to shift said support and the fold roller carried thereby toward said other fold roller and reduce the space between said rollers in consequence of the reduction in number and thickness of the webs being fed through said rollers resulting from the breaking of said one web whereby to instantly regrip the reduced-thickness remaining web tightly between said rolls and prevent jamming thereof.

8. An automatic safety readjustment device for a newspaper printing press having paired second fold rollers and an adjacently-disposed folding-and-tucking cylinder and blade cooperating therewith uniting two separate multi-strip continuously running paper webs proceeding to a junction at said cylinder along two separate web paths, said device comprising a shiftable support mounted on said press and carrying one of said fold rollers, mechanism including a fluid pressure motor operatively connected to said support for shifting said support and the fold roller carried thereby toward the other fold roller of the pair to narrow the gap therebetween, and a web breakage detector disposed adjacent one of said webs on one of said separate paths and operatively connected to said mechanism, said web breakage detector being responsive to the breakage of said web for energizing said mechanism to shift said support and the fold rollers carried thereby toward said other fold roller and reduce the space between said rollers in consequence of the reduction in number and thickness of the webs being fed through said rollers resulting from the breaking of said one web whereby to instantly regrip the reduced-thickness remaining web tightly between said rolls and prevent jamming thereof.

9. An automatic safety readjustment device for a newspaper printing press having paired second fold rollers and an adjacently-disposed folding-and-tucking cylinder and blade cooperating therewith uniting two separate multi-strip continuously running paper webs proceeding to a junction at said cylinder along two separate web paths, said device comprising a shiftable support mounted on said press and carrying one of said fold rollers, mechanism including a fluid pressure motor and a control valve connecting said motor to a source of pressure fluid operatively connected to said support for shifting said support and the fold roller carried thereby toward the other fold roller of the pair to narrow the gap therebetween, and a web breakage detector disposed adjacent one of said webs on one of said separate paths and operatively connected to said control valve, said web breakage detector being responsive to the breakage of said web for energizing said control valve to shift said support and the fold roller carried thereby toward said other fold roller and reduce the space between said rollers in consequence of the reduction in number and thickness of the webs being fed through said rollers resulting from the breaking of said one web whereby to instantly regrip the reduced-thickness remaining web tightly between said rolls and prevent jamming thereof.

10. An automatic safety readjustment device

16

for a newspaper printing press having paired second fold rollers and an adjacently-disposed folding-and-tucking cylinder and blade cooperating therewith uniting two separate multi-strip continuously running paper webs proceeding to a junction at said cylinder along two separate web paths, said device comprising a shiftable support mounted on said press and carrying one of said fold rollers, mechanism including a motive element operatively connected to said support and normally urging said support and the fold roller carried thereby toward the other fold roller of the pair to narrow the gap therebetween, a releasable locking arrangement engaging and releasably holding said support from motion toward said other roller, and a web breakage detector disposed adjacent one of said webs on one of said separate paths, and operatively connected to said locking arrangement, said web breakage detector being responsive to the breakage of said web for energizing said locking arrangement to release said support whereby to shift said support and the fold roller carried thereby toward said other fold roller and reduce the space between said rollers in consequence of the reduction in number and thickness of the webs being fed through said rollers resulting from the breaking of said one web whereby to instantly regrip the reduced-thickness remaining web tightly between said rolls and prevent jamming thereof.

11. An automatic safety readjustment device for a newspaper printing press having paired second fold rollers and an adjacently-disposed folding-and-tucking cylinder and blade cooperating therewith uniting two separate multi-strip continuously running paper webs proceeding to a junction at said cylinder along two separate web paths, said device comprising a shiftable support mounted on said press and carrying one of said fold rollers, mechanism including a spring operatively connected to said support and normally urging said support and the fold roller carried thereby toward the other fold roller of the pair to narrow the gap therebetween, a releasable locking arrangement engaging and releasably holding said support from motion toward said other roller, and a web breakage detector disposed adjacent one of said webs on one of said separate paths and operatively connected to said locking arrangement, said web breakage detector being responsive to the breakage of said web for energizing said locking arrangement to release said support whereby to shift said support and the fold roller carried thereby toward said other fold roller and reduce the space between said rollers in consequence of the reduction in number and thickness of the webs being fed through said rollers resulting from the breaking of said one web whereby to instantly regrip the reduced-thickness remaining web tightly between said rolls and prevent jamming thereof.

12. An automatic safety readjustment device for a newspaper printing press having paired second fold rollers and an adjacently-disposed folding-and-tucking cylinder and blade cooperating therewith uniting two separate multi-strip continuously running paper webs proceeding to a junction at said cylinder along two separate web paths, said device comprising a shiftable support mounted on said press and carrying one of said fold rollers, mechanism including a spring operatively connected to said support and normally urging said support and the fold roller carried thereby toward the other fold roller of the pair to narrow the gap therebetween, a re-

leasable locking arrangement engaging and releasably holding said spring out of operation and preventing said support from motion toward said other roller, and a web breakage detector disposed adjacent one of said webs on one of said separate paths and operatively connected to said locking arrangement, said web breakage detector being responsive to the breakage of said web for energizing said locking arrangement to release said support whereby to shift said support and the fold roller carried thereby toward said other fold roller and reduce the space between said rollers in consequence of the reduction in number and thickness of the webs being fed through said rollers resulting from the breaking 15

of said one web whereby to instantly regrip the reduced-thickness remaining web tightly between said rolls and prevent jamming thereof.

LESLIE J. GRINER.
